UNITED STATES PATENT OFFICE

160,360

DISPLAY CABINET

Edvin F. Bjoro and John M. Fisher, Huntington,
N. Y., assignors to The Spool Cotton Company,
Newark, N. J., a corporation of New Jersey

Original application April 2, 1946, Serial No.
128,172. Divided and this application November
24, 1947, Serial No. 142,739

Term of patent 14 years

(Cl. D80—11)

To all whom it may concern:

Be it known that we, Edvin F. Bjoro and John M. Fisher, citizens of the United States, residing at Huntington, L. I., and village of Huntington Bay, Huntington, L. I., respectively, in the county of Suffolk and State of New York, have invented a new, original, and ornamental Design for a Display Cabinet, of which the following is a specification, reference being had to the accompanying drawing, forming a part thereof.

Fig. 1 is a front perspective view of the display cabinet showing our new design; Fig. 2 is a front elevational view thereof; Fig. 3 is a side elevational view;

This application is a division of application Serial No. D. 128,172, filed April 2, 1946, now abandoned.

We claim:

The ornamental design for a display cabinet, as shown.

EDVIN F. BJORO.
JOHN M. FISHER.
